UNITED STATES PATENT OFFICE

133,915

DESIGN FOR A CRUTCH

Thornton S. Penn, Des Moines, Iowa

Application May 26, 1942, Serial No. 107,016

Term of patent 7 years

To all whom it may concern:

Be it known that I, Thornton S. Penn, a citizen of the United States and a resident of Des Moines, in the county of Polk and State of Iowa, have invented a new, original, and ornamental Design for a Crutch, of which the following is a specification, reference being had to the accompanying drawing, forming a part thereof.

Figure 1 is a side elevational view of a crutch, showing my design;

Figure 2 is a front elevational view; and
Figure 3 is an enlarged sectional view taken
on the line 3—3 of Figure 1.

I claim:

The ornamental design for a crutch, substantially as shown.

THORNTON S. PENN.
